CLAIM

The ornamental design for an electric pressure washer as shown and described.

DESCRIPTION

FIG. 1 is a front, right, and bottom side perspective view of an electric pressure washer showing our new design;

FIG. 2 is a rear, left, and top side perspective view of the electric pressure washer shown in FIG. 1;

FIG. 3 is a front elevational view of the electric pressure washer shown in FIGS. 1 and 2;

FIG. 4 is a rear elevational view of the electric pressure washer shown in FIGS. 1-3;

FIG. 5 is a left-side elevational view of the electric pressure washer shown in FIGS. 1-4;

FIG. 6 is a right-side elevational view of the electric pressure washer shown in FIGS. 1-5;

FIG. 7 is a top plan view of the electric pressure washer shown in FIGS. 1-6;

FIG. 8 is a bottom plan view of the electric pressure washer shown in FIGS. 1-7.

FIG. 9 is an enlarged view of the portion marked '9' on the electric pressure washer shown in FIG. 1;

FIG. 10 is an enlarged view of the portion marked '10' on the electric pressure washer shown in FIG. 1;

FIG. 11 is an enlarged view of the portion marked '11' on the electric pressure washer shown in FIG. 2;

FIG. 12 is an enlarged view of the portion marked '12' on the electric pressure washer shown in FIG. 2; and,

FIG. 13 is an enlarged view of the portion marked '13' on the electric pressure washer shown in FIG. 4.

The broken lines shown in the drawings illustrate portions of the electric pressure washer that form no part of the claimed design.

(Continued)

The dot-dashed broken lines in the drawings indicate cutoff boundaries for the enlarged detailed portion views of the electric pressure washer and form no part of the claimed design.
